COMBINED SHOE HORN, GARMENT HANGER AND FOLDING BRUSH

Albert Wetfberg, 6124 Beerfelden, Beerfelden,
Odenwald, Germany

Filed June 23, 1964, Ser. No. 80,729

Term of patent 14 years

(Cl. D9—2)

Fig. 1.

Fig. 2.

Fig. 3.

FIG. 4.FIG. 5.

FIG. 2 is a rear elevational view thereof;

FIG. 3 is an end elevational view;

FIG. 4 is a front perspective view thereof, shown in open position; and

FIG. 5 is a rear perspective view of FIG. 4.

I claim:

The ornamental design for a combined shoe horn, garment hanger and folding brush, substantially as shown and described.
